Primary Examiner — Terry Wallace(74) *Attorney, Agent, or Firm* — Lowe Graham Jones PLLC**CLAIM**

I claim the ornamental design for the microwave cover colander, as shown and described.

DESCRIPTION

FIG. 1 is a perspective view of the microwave cover colander, showing my new design.

FIG. 2 is a top view of the microwave cover colander.

FIG. 3 is a front view of the microwave cover colander, the back view, left side view, and right side view being identical; and,

FIG. 4 is a bottom view of the microwave cover colander.

1 Claim, 3 Drawing Sheets# US D671,803 S
